UNITED STATES PATENT OFFICE.

JOHN F. ISBELL, OF ALHAMBRA, CALIFORNIA; CLEMENTINE ISBELL, ADMINISTRATRIX OF SAID JOHN F. ISBELL, DECEASED, ASSIGNOR OF ONE-HALF TO OTTO Q. BECKWORTH, OF LOS ANGELES, CALIFORNIA; CLAUDIA I. SILVEY ADMINISTRATRIX OF THE ESTATE OF SAID JOHN F. ISBELL, DECEASED.

RESILIENT SUSPENSION MEANS FOR SCREEN SEPARATORS.

Application filed June 19, 1922. Serial No. 569,496.

This invention pertains generally to inclined screen separators, for separating and sizing sand, gravel, crushed rock, ores and similar materials; and consists of new and 5 improved means for yieldingly supporting the separating screen, in a manner to greatly increase its efficiency and capacity.

The vibrator mechanism which I employ in connection with the screen embodying 10 the herein disclosed invention, is shown and described in a copending application, filed on the 19th day of June, 1922, Serial Number 569,495. In the aforesaid copending application the invention not only embraces 15 the vibrator mechanism, but also embraces its use in connection with a yieldingly mounted separator screen; while the present invention is limited to the particular construction of the screen and the manner of 20 yieldingly or resiliently mounting it adjacent the vibrator mechanism.

The particular object of the present invention is the provision of a yielding mounting means for a screen separator, so that it 25 may receive its vibratory motion directly upon the central suspended area of the screen, from a vibrator mechanism mounted adjacent thereto, and whereby the vibrations so transmitted to it will not be limited to 30 such central suspended area, but the resultant vibratory motion will be effective throughout its entire surface, thereby adding greatly to its efficiency and capacity.

In this particular case I provide a means 35 whereby the screen may not only be yieldingly suspended, so as to be sensitive and particularly susceptible to the transmitted vibrations over its entire surface, but also so this yielding support may be adjustable 40 to make the screen as a whole more or less elastic and more or less susceptible to the transmitted vibrations. That is, so the transmitted vibrations will result in agitating the screen either in a series of quick, 45 sharp vibrations of small amplitude, or a series of less frequent and larger vibrations of comparatively greater amplitude.

The details of construction and function 50 of my improvements are fully set forth in the following specification, reference being made therein to the accompanying drawings; in which—

Fig. 1 is a side elevation of my assembled separators; Fig. 2 is a plan view thereof; Fig. 3 is a longitudinal vertical section taken 55 as indicated by the line 3—3 of Fig. 2; Fig. 4 is a transverse vertical section as indicated by the line 4—4 of Fig. 3; Fig. 5 is an enlarged fragmentary perspective view of the yielding screen support; Fig. 6 is an 60 enlarged fragmentary detail view, taken as indicated by the line 6—6 of Fig. 3; Fig. 7 is an enlarged detail view of the adjustable clamp, taken as indicated by the line 7—7 of Fig. 6; and Fig. 8 is an enlarged fragmentary detail view, taken as indicated by the line 8—8 of Fig. 6.

While the details of construction and operation of my improved vibrating mechanism are shown and described in my aforementioned copending application, together with a screen of the type and construction comprising the present invention; I will nevertheless describe, in a general way, 70 enough of the details of construction and 75 method of operation of that vibrating mechanism to make the operative function of the present screen and its method of suspension clearly understandable.

Referring now to the drawings, and particularly to Fig. 1, the screen—generally designated by the numeral 10—and the vibrator mechanism—generally designated by the numeral 11—are mounted upon a main frame 12; the latter being ordinarily 85 supported in an inclined position upon suitable corner posts 13, and cross or brace members 14. These members may be constructed of any suitable material, and while I have herein shown them as being constructed of wood, they, nevertheless, can be constructed of metal if desired. Under ordinary circumstances the material to be separated is fed to the screen (which is supported within the main frame 12) over 90 a feed chute or distributor 15, which may be provided with any suitable means for properly distributing material across the upper receiving end of the screen. The fines or undersized materials passing through the 95 screen, fall into a chute 16, extending over the entire bottom of the main frame 12, from which they may gravitate to a suitable receptacle, as shown at 17. The over-

sized materials or tailings which do not pass through the screen gravitate down over its surface and fall into the chute 18, which conveys them to a suitable receptacle, as shown at 19.

The main frame 12 consists of two parallel longitudinal side members 20, and two parallel transverse members 21, secured together in any suitable manner. The vibrator mechanism 11 is supported upon this main frame upon two parallel tubular supporting members 22, extending transversely across the frame and having their ends supported in bearing blocks 23 and 24. The upper blocks 23 are simple bearing blocks, while the lower blocks 24 are in the nature of pillow blocks, having removable tops 24^a secured in place by cap screws 25. This is to permit the raising of the vibrator mechanism and screen from the position shown in solid lines in Fig. 1, to that shown in dotted lines, for the purpose of replacing or repairing the screen; and in such instance the upper tubular supporting member 22, rotating in its bearing blocks 23, serves as a fulcrum. Cap screws 26 in the tops of the bearing blocks 23 and 24 serve to hold the tubular supporting members 22 against axial movement therein; these, however, may be loosened when it is desired to raise the mechanism as just described.

The vibrator mechanism is carried directly upon the members 22 by means of a pair of parallel frame members, generally designated by the numeral 27. These are identical and each consists of base supporting members 28, and standards 29, formed either integral or separable as desired. In the present case I have shown them to be formed integral. The base members 28 extend longitudinally across the screen and are adjustably supported upon the members 22 by means of split bearing clamps 30, formed integral with their ends. The bearing clamps 30 are clamped about the tubular members 22 in the usual manner, as by means of bolts 31 extending through suitably formed lugs or ears thereon. In this manner the frame members 27 are made longitudinally adjustable upon the supports 22, so that the distance between them may be varied or their positions may be altered relative to the surface of the screen 10. The standards 29 each consists of a pair of legs 29^a extending upwardly from the base members 28; these legs being joined intermediate their ends by an integral transverse brace member 32, and at their top ends by a removable cap 33 secured in place by cap screws 34. Bearing blocks 35 are mounted between the contiguous faces of the legs 29^a, intermediate the transverse braces 32 and removable caps 33; these blocks having channels in their vertical edges to engage the sides of the legs to hold them against trans-

verse movement. The blocks are made vertically adjustable in this space by means of screws 36, extending loosely through central bores 33^a in the caps 33, and screw-threadedly engaging internally screw-threaded bores 37 in the tops of the blocks. Lock nuts 38 hold the screws 36 against axial movement in the bores 33^a. Thus by rotation of screws 36, blocks 35 may be vertically adjusted between the legs 29^a.

A transverse shaft 39 is revolvably journaled in suitable bearings in the blocks 35; and a belt pulley 40 is keyed to it intermediate the frame members 27; a pair of spacer blocks 41 being similarly fixed to the shaft 39 on either side of the pulley 40 to maintain it in its central position. A drive pulley 42 is keyed to the outer end of the shaft 39; and a pulley 43 is loosely mounted on the outer end of this shaft to which the drive belt 44 may be shifted when it is desired to put the vibrator mechanism out of operation. The drive belt 44 may be operated from any suitable source of motive power.

A rocker arm—generally designated by the numeral 45—hereinafter termed the “vibrator beam” is rigidly mounted upon a rock shaft 46 by means of a central split bearing 47; each end of this shaft being journaled in suitable bearings 48 in the supporting members 28 of frame members 27. The vibrator beam 45 consists of a pair of coplanar arms 49 extending outwardly from opposite sides of the split bearing 47, at right angles to its axis and in alignment with each other; terminating at their outer ends in tubular hammer members 50 having central bores extending at substantially right angles to the plane of the coplanar arms 49, as shown in Fig. 3. A pair of arms 52, preferably formed integral with the bearing 47, extend upwardly therefrom in spaced relation, and at substantially an angle of 90° with the arms 49. A belt pulley 53 is revolvably mounted upon a shaft 54, carried in suitable bearings in the upper ends of the arms 52; this pulley 53 being driven from the pulley 40 by means of a belt 55. The pulley 53 is unbalanced by weights 56 being secured to it eccentrically, so that during its rotation these weights will have a tendency to throw it off center and impart an oscillatory motion to the vibrator beam, as indicated by the arrows in Fig. 3.

A cushioning adjustment is provided intermediate the vibrator beam 45 and the frame members 27, by means of studs or pins 59 carried upon the upper edges of the arms 49, on either side of and equidistant from the shaft 46; these studs extending through apertures in bridge members 58 carried upon and between the frame members 27; and having helical springs 59^a surrounding them and confined between the bridge members 58 and adjusting nuts 60 on their upper

ends. By adjusting the compression of the springs 59, by rotation of the nuts 60 upon the upper ends of studs 57, the oscillatory motion of the vibrator beam 45 may be cushioned to vary the force of the vibratory impacts transmitted to the screen 10.

It may be here noted that vertical adjustment of the bearing blocks 35 upon the standards 29 will adjust the tension of the 10 drive belt 55 intermediate pulleys 40 and 53, which will also have a cushioning effect upon the oscillatory motion transmitted to the vibrator beam by rotation of the unbalanced pulley 53. In all cases the tension 15 of the belt 55 will be such as to permit this oscillatory movement, and it may be so adjusted by relative positioning of the pulley 40 as to have little or no limiting effect upon the motion of the vibrator beam, or 20 as to have the cushioning effect, to limit this motion, above described.

The construction of the screen 10 is as follows:

A pair of longitudinal side rails 61, extend 25 between and parallel with the longitudinal side frame members 20, and the screen fabric 62 is supported upon and between these rails, with its top and bottom edges open or unobstructed to receive and 30 discharge the materials. The side rails 61 are preferably constructed of channel irons 62, mounted with their web faces inwardly toward each other and their channel faces outwardly, as shown in Figs. 4 and 6. The 35 screen fabric is stretched taut across and between the bottom flanges of the channels 62, and thence brought around their outer edges and into the channels; being thus held in place by means of wedged blocks 63 secured 40 in the channels by bolts 64 extending through the webs. It will be noted that the wedge blocks 63 have tapered top and bottom edges to conform to the inner inclined faces of the channel flanges. In this 45 manner the screen fabric 62 is held tightly clamped upon the channels 63, and this means is also effective in drawing the screen taut when a light or fine mesh screen is used. The rails 61 are braced and held rigidly in 50 spaced relation by means of transverse brace rods 66; these rods being secured to the rails by means of base blocks 67. These blocks have flanges through which the bolts 65 may extend, and the rods 66 have a screw-threaded connection with them, so that this 55 means may also be utilized for spreading the rails 61 for drawing the screen fabric 62 taut. Reinforcing members 68 extend transversely between the side rails 61, along and 60 beneath the top and bottom edges of the screen fabric 62. These reinforcing members may be made on angle iron, of suitable size, secured at each end to the rails 61 by bolts 69. The screen fabric 62 is secured to 65 the reinforcing members 68 by suitable bolts

70; these bolts having round heads protruding above the screen surface to offer as little obstruction as possible to the material passing over it. A resilient member 71 extends longitudinally beneath the screen fabric 62, being secured at each end to the reinforcing members 68, as by means of bolts 72. This member is preferably constructed of resilient flat metal, such as spring steel, 75 and extends in a plane directly beneath and in alignment with the vibrator beam 45. I will shortly explain the function of the member 71.

The screen 10 is yieldingly suspended from the supporting members 22, by means 80 of hangers 73 hingedly connected at their upper ends to the outer ends of resilient supporting bars 74; the latter being adjustably secured to the members 22 by means of clamps 75. The hinged connection between 85 the hangers 73 and supporting bar 74 is clearly illustrated in Fig. 5, and is preferably formed as there shown; the connection being made by a hinge pin 76, in the form of a bolt which may be removed to permit the removal of the screen 10 from the rest of the mechanism for replacement or repairs. The hangers 73 are preferably formed of flat metal, as shown, and may be secured to the rails 61, intermediate the blocks 90 67 and channels 63 by the bolts 65 extending through suitably spaced apertures 77. This hinged connection permits lateral motion of the screen 10 relative to the main frame 12, during operation of the vibrating 95 mechanism. If desired, the hangers 73 may be replaced by shackles or link connections.

The supporting bars 74 are preferably constructed of thin flat metal, such as spring 100 steel; and are so mounted upon the supporting members 22 that their resilient action may be varied to permit varying degrees of vertical motion of the screen; that is, at right angles to the plane of the screen fabric 62. This yielding or vibratory motion is varied 105 by means of the adjustable clamps 75, which are illustrated in detail in Figs. 6 and 7. They consist of U-bolts 78 adapted to extend over and embrace the tubular supporting members 22, and thence extend through suitable apertures 79 in clamp blocks 80; the latter having central arcuate notches cut in their tops to embrace the opposite sides of the tubular supporting members 22, as shown 110 in Fig. 7. The straight portions of the U- 115 bolts 78 thence extend through apertures 81 in clamp plates 82 and receive nuts 83 on their outer ends. The spring bar 74 is clamped intermediate the blocks 80 and plates 82 and between the legs of the U-bolts; 120 and when the nuts 83 are tightened upon the U-bolts the bars 74 and tubular supporting members 22 are clamped in rigid connection. By loosening the nuts 83 the clamps 75 may 125 be moved axially along supporting members 130

- 22 to lengthen or shorten the distance intermediate these clamps and the hinged connections between hangers 73 and bars 74. It is obvious that this adjustment will increase or diminish the extent to which the frame 10 may vibrate vertically, depending upon the extent to which the distance intermediate the hinged connections and clamps is lengthened or shortened.
- 10 Studs 84, having heads 85, extend upwardly through the bar 71 and screen fabric 62, in axial alignment with bores 51 in hammer ends 50 of the vibrator beam 45, when the latter is in its normal central position; 15 that is, when the arms 49 are parallel to the surface of the screen fabric 62. Lock nuts 86 serve to hold the studs 84 in place and washers intermediate these nuts engage the screen fabric 62 to hold it down upon the bar 71. The upper screw-threaded ends of studs 84 engage in internally screw threaded bores 87 in adjusting sleeves 88; and studs 89, having heads 90, likewise screw-threadedly engage in the bores 87 from their opposite ends, as clearly shown in Fig. 3. The sleeves 88 are longitudinally slit inwardly from each end, on opposite sides, and provided with clamping bolts by means of which the sleeves may be held or clamped in adjusted position upon the studs 84 and studs 39 may be similarly clamped in adjusted position in the bores 87.
- It will be seen that the studs 89 extend loosely through the bores 51 in the hammer ends 50 of arms 49, so that during oscillatory movement of the vibrator beam 45 the top and bottom faces of the ends 50 will successively impact against the top faces or ends of the sleeves 88 and the undersides of heads 90 upon studs 89. It will also be noted that when the lower face of one end 50 is impacting against the top face of one of the sleeves 88, the top face of the opposite end 50 will be impacting against the underside of the head 90 of one of the studs 89. The sleeves 88 and studs 89 are made adjustable relative to the screen fabric 62 and the ends 50 of the vibrator beam, so that the spaces intermediate the opposite ends of the ends 50 and the top faces of sleeves 88 and bottom faces of heads 90 of studs 89 will be exactly equal when the vibrator beam is in its normal central position; that is, parallel to the surface of the screen fabric 62. From the foregoing it is clear that this adjustment of the sleeves 88 and studs 89 relative to the ends of the vibrator beam will govern the force and amplitude of the vibratory impacts delivered to the screen. Also, that the impacts delivered will be in the nature of impacts or blows administered successively to opposite faces of the screen fabric 62. By lengthening the distance between the underside of heads 90 and the top faces of the sleeves 88, 60 the vibrations or impacts will be less frequent

and of greater amplitude, while by shortening this distance the vibrations will be more rapid and intense, and of less amplitude.

In addition to the vibratory impacts thus delivered to the screen fabric 62, through 70 the medium of connections with the bar 71, the yielding means for suspending the screen 10 from the frame, as hereinbefore described, permits resultant vibration of the rails 61, so the entire surface of the screen fabric 75 will be susceptible to these transmitted impulses, and the vibratory effect set up over the entire screen surface adjacent the side rails 61 as well as throughout its central area, thereby greatly adding to the capacity 80 and efficiency of the screen. The adjustable suspension means for the screen 10 to either increase or diminish its sensitiveness to the vibratory impulses delivered by the mechanism 11, permits it to be set in accord with 85 the several adjustments of the vibrating mechanism to efficiently handle a great many different kinds and characters of materials as well as separating them into various degrees of fineness. 90

While I have herein shown and described a preferred specific embodiment of my invention, and its combination with a vibrator mechanism, I nevertheless reserve the right to make such changes or modifications in 95 structure and arrangement, as will properly come within the scope of the appended claims.

Having described a preferred form of my invention, I claim:

1. In a screen separator, the combination of a screen, a yielding suspension member for the screen comprising a flat spring member extending flat side to the screen, spaced connections between said spring member and the screen, and supporting members engaging the spring member at points spaced from the screen connections. 105

2. In a screen separator, the combination of a frame, a screen and yielding supporting means for the screen comprising a resilient bar, spaced connections between said bar and screen, and spaced connections between the bar and frame also spaced from the screen connections. 110

3. In a screen separator, the combination of a frame, a screen and yielding supporting means for the screen comprising a resilient bar, spaced connections between the bar and screen, and spaced connections between the bar and frame, also spaced from the screen connections, the last mentioned connection being longitudinally movable on the bar to vary the extent it will normally vibrate. 120

4. A screen separator comprising a frame, 125 a screen, means for yieldingly supporting the screen upon the frame so it can vibrate freely, said means comprising a resilient member extending substantially parallel to the screen surface, connection between said 130

member and the screen and between it and the frame, the last mentioned connection being adjustably movable longitudinally of the resilient member whereby the normal yielding movement of said member may be varied.

5. A screen separator comprising a frame, a screen, means for yieldingly supporting the screen upon the frame so it can vibrate freely, said means comprising a plurality of 10 resilient members extending across the screen substantially parallel to its surface, the screen being suspended upon said members by depending connections adjacent their ends, and connections between said resilient 15 members and the frame, said connections being adjustable longitudinally upon said members whereby the extent of their yielding movement may be varied.

6. A screen separator comprising a frame, 20 a screen, means to vibrate said screen, means for yieldingly supporting the screen upon the frame, said means comprising a yielding member extending across the screen and connected thereto at its ends, and means intermediate the ends of said member connecting it to the frame.

7. A screen separator comprising a frame, a screen, means for yieldingly supporting the screen upon the frame so it can vibrate 30 freely, said means comprising a plurality of flat resilient bars extending across the screen substantially parallel with its surface and connected thereto at their ends, said members being yielding in a direction perpendicular to the screen surface, and connections between said bars and the frame, said 35 connections being spaced intermediate the ends of the bars and longitudinally adjust-

able thereon to vary the extent of their yielding movement.

8. In a device for separating materials the combination of a supporting frame, a screen, means for yieldingly supporting said screen upon the frame, said means comprising a yielding member secured at its ends to the 45 screen, and clamping members connecting said yielding member intermediate its ends to the frame, said clamping members being independently longitudinally movable on the yielding member to vary the extent of its 50 yielding movement.

9. In a screen separator the combination of a supporting frame comprising longitudinal and transverse members, a screen, a vibrator mechanism carried by the transverse 55 frame members adapted to deliver vibrating impulses to the screen in a direction transverse to the plane of its surface, yielding members secured at each end to the screen and extending substantially parallel to the said transverse frame members, said members being yielding in a direction substantially perpendicular to the screen surface, clamp members carried by the transverse frame members and engaging the yielding 60 members intermediate their ends, the said clamp members being independently longitudinally adjustable on the frame and yielding members to vary the extent of vibratory 65 movement of the material supporting member.

In witness that I claim the foregoing I have hereunto subscribed my name this 2nd day of June, 1922.

JOHN F. ISBELL.
